CLAIM

We claim the ornamental design for a cell for a shade, as shown and described.

DESCRIPTION

This application is related to U.S. Design patent application Ser. No. 29/389,786, filed Apr. 15, 2011, now U.S. Design Pat. No. D668,090, and entitled “Cell for a Shade”.

FIG. 1 is a perspective view of a cell for a shade of the present invention.

FIG. 2 is an enlarged perspective view of the cell of FIG. 1.

FIG. 3 is a front elevation view of the cell of FIG. 1.

FIG. 4 is a top plan view of the cell of FIG. 1.

FIG. 5 is a side elevation view of the cell of FIG. 1.

FIG. 6 is a rear elevation view of the cell of FIG. 1; and,

FIG. 7 is a bottom plan view of the cell of FIG. 1.

The broken lines shown in the drawings are for purposes of illustrating use and environment only and form no part of the claimed design.
